UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,141, dated September 29, 1896.

Application filed August 24, 1896. Serial No. 603,800. Term of patent 3½ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of an applique style of design having a stitch-like outline and arranged in the form of large panels in which are placed large ornaments of said applique style of design with stitch-like outline, as represented in the accompanying drawing.

The border for the said design is also formed of an applique style of design having a stitch-like outline and arranged in the form of large open panels with large ornaments of said applique style of design in said panels, as shown 20 in the drawing.

What I claim is—

1. The design for wall-paper herein shown and described.
2. In the design for wall-paper the border 25 herein shown and described.

Witness my hand this 10th day of August, 1896.

CHARLES BOOZ.
